FLAG POLE HOLDER

Abe Murdock, 4835 Calvert St., Washington, D.C.
Filed July 13, 1962, Ser. No. 209,591
9 Claims. (Cl. 248—44)

This invention generally relates to an article supporting device, and more particularly to a novel holder for the staff or pole of a flag or the like.

In supporting a staff or a pole, carrying a flag or any object having a substantial surface area, it is difficult to have it stand up against jars or slight wind pressures. Moreover, the wind frequently causes the flag to foul about the pole. In addition, it is often difficult, particularly on sloping ground, to secure the staff or pole in an erect position. Furthermore, it is usually difficult to drive a long pole member firmly into the ground so that it will remain in an erect position.

Therefore, the principal object of the present invention relates to a novel supporting device for supporting the pole or staff of a flag or the like.

A further object of this invention relates to a novel holder for flag staffs or the like which is relatively light in weight and is easy and inexpensive to manufacture.

An additional object of this invention relates to a novel supporting device for the pole or staff of a flag which prevents fouling of the flag about the pole.

A further object of this invention relates to a flag pole which is particularly adapted to be utilized with my novel supporting device.

Other objects and the entire scope of the present invention will become apparent from the following detailed description and by reference to the accompanying drawing. It should be understood, however, that the detailed description and specific examples while indicating preferred embodiments of the invention, are given by way of illustration only since various changes and modifications within the spirit and scope of the invention will become apparent as the description herein progresses. Reference now being made to the accompanying drawing which form a part hereof.

FIGURE 1 is a view in perspective of the supporting device in its active use for supporting my preferred flag staff from the ground;

FIGURE 2 is a front elevational view, partly in section, of the device mounted in the ground and supporting a flag staff or the like;

FIGURE 3 is a side elevational view of the device mounted in the ground and supporting a flag staff or the like;

FIGURE 4 is a section taken on line 4—4 of FIGURE 2;

FIGURE 5 is a view similar to FIGURE 1 showing a modified form of the present invention.

In the drawing numeral 1 generally indicates my novel supporting device being utilized to support my preferred flag pole.

As best shown in FIGURES 1-3, the holder comprises four parts, a generally U-shaped member 2, a tubular member 3, a pointed rod member 4 and an apertured pad member 9.

The U-shaped member, which may be fashioned from a length of suitable strap material, includes a horizontal element 6 having a centrally located aperture 7 and two vertically depending legs 5. The elements 5 are each provided with pointed or sharpened lower ends 8, to facilitate insertion of the same into the ground.

The tubular member 3 is adapted to be rotatably received by aperture 7 by providing a slight clearance between the outside diameter of the tubular member and the walls of the aperture. The inside diameter of the

2

tubular member 3 is such as to permit rod member 4 to be rotatably received and the pole 11, which is to be supported, to be slidably received therein.

Rod member 4 is preferably somewhat shorter than tubular member 3 and longer than legs 5. As best seen in FIGURE 2, the rod member is pointed at one end to facilitate insertion of the same into the ground.

Pad member 9 is preferably washer shaped, having a centrally located aperture 10. The outside diameter of pad member 9 is somewhat smaller than the distance between the inwardly facing surfaces of legs 5. As best seen in FIGURE 2, the diameter of aperture 10 is smaller than the outside diameter of tubular member 3 in order that the pad member 4 rotatably support the end of tubular member 3. In addition, the diameter of aperture 10 must be sufficient to permit rod member 4 to pass therethrough and enter the ground.

The flag staff or pole 11, preferably comprises a plurality of tubular sections adapted to completely telescope or concentrically nest within one another when not extended in operative relation. There is thus provided a compact unit which is both easy to store and transport. The tubular pole sections are preferably retained in extended relation by means of bolts 12, which extend through the overlapping ends of adjacent sections, as best seen in FIGURE 1.

When my preferred telescoping flag pole is utilized, the tubular member 3, which rotatably rests upon pad member 9, may form the lower-most section of the flag pole 11.

The operation of my novel device is best seen in FIGURES 1 and 2. A substantial portion of legs 5 of the U-shaped member 2 are embedded vertically in the ground. The apertured pad member 9 is located on the ground between the legs 5 with the aperture 10 vertically aligned with aperture 7 in horizontal element 6. Pointed rod member 4 is positioned centrally within aligned apertures 7 and 10 and a portion thereof is embedded in the ground. The upper end of rod member 4 extends above horizontal element 6. The tubular member 3, or if my preferred telescoping flag pole is employed, the lower-most tubular section thereof, is received by aperture 7 and is rotatably supported by pad member 9. The portion of rod member 4 which extends above pad member 9 is rotatably received within the bore of the tubular member. The upper-most sections of my telescoping flag pole are secured to the upper end of the tubular member. In the event my preferred telescoping flag pole is not employed, it is a simple matter to secure the staff or pole to the upper end of tubular member 3.

The present invention will thus be seen to completely and effectively accomplish the objects enumerated hereinabove. My novel device provides a simple and secure means of supporting a flag pole, or the like, in an erect position. In addition, because of my novel construction, the tubular member, which is rotatably supported upon the pad member is free to rotate about the rod member and within the aperture in the horizontal element of the U-shaped member. Thus the fouling or twisting of the flag around the pole due to wind turbulence is prevented since the pole will rotate as the wind tends to foul the flag.

In the modification of my novel device shown in FIGURE 5, it will be seen that the horizontal member 13 may have only one depending leg member 14.

It will be realized, however, that various changes and substitutions may be made to the specific embodiments disclosed herein for the purposes of illustrating the principles of this invention, without departing from these principles. Therefore, this invention includes all modifications encompassed within the spirit and scope of the following appended claims.

What is claimed is:

1. A flag pole supporting device comprising in combination a generally U-shaped member comprising a horizontal element having a first aperture therein and at least two vertical depending elements having pointed lower ends adapted to be driven into the ground so as to be in rigid engagement therewith, a tubular flag pole receiving member adapted to be rotatably received by said first aperture, a pad member having a second aperture therein, said aperture communicating with the bore of said tubular member when said tubular member is vertically and rotatably supported by said pad member and a rod member adapted to be received by said tubular member and said second aperture while inserted into the ground so as to be in rigid engagement therewith.

2. A flag pole supporting device comprising in combination a generally U-shaped member comprising a horizontal element having a first aperture therein and two vertical depending elements, said vertically depending elements being adapted to be inserted into the ground so as to be in rigid engagement therewith, a pad member having a second aperture therein, said pad member adapted to engage the ground and be received within said depending elements with said first and second apertures in vertical alignment, a tubular member adapted to be rotatably received by said first aperture and further adapted to be rotatably supported by said pad member when the bore of said tubular member communicates with said second aperture, and a rod member adapted to be rotatably received by said tubular member and extend into the ground in rigid engagement therewith through said second aperture.

3. A flag pole supporting device as set forth in claim 2, wherein said vertical depending elements have pointed lower ends to facilitate insertion into the ground.

4. A flag pole supporting device as set out in claim 3 wherein said rod member is pointed at one end to facilitate insertion into the ground.

5. A supporting device for a pole having a lower-most tubular portion, comprising in combination a generally U-shaped member comprising a horizontal element having a first aperture therein, and at least two vertical depending elements adapted to be inserted into the ground so as to be in rigid engagement therewith, said first aperture being adapted to rotatably receive the lowermost tubular portion of the pole to be supported, a pad member having a second aperture therein and adapted to rotatably support the lower-most tubular portion of the pole to be supported, said pad member being also adapted to be received between said depending elements with said first and second apertures in vertical alignment, and a rod member adapted to be received by said first and second apertures, said rod member being further adapted to be inserted into the ground so as to be in rigid engagement therewith and rotatably received by the lower-most tubular portion of said pole.

6. A supporting device as set forth in claim 5, wherein in said vertical depending elements have pointed lower ends to facilitate insertion into the ground.

7. A supporting device as set out in claim 6, wherein said rod member is pointed at one end to facilitate insertion into the ground.

8. A flag pole supporting device including in combination a horizontal element having a first aperture therein and at least one vertically depending leg element, the free end of said leg element being adapted to be inserted into the ground so as to be in rigid engagement therewith and thereby support said horizontal element in vertically spaced relation above the surface of the ground, a pad member having a second aperture therein, said pad member being adapted to engage the ground and underlie said horizontal element so that said first and second apertures are in vertical alignment, an elongated rod member adapted to be received within said first and second apertures when they are in vertical alignment and be inserted into the ground so as to be in rigid engagement therewith, said rod member being of sufficient longitudinal extent so as to extend vertically above said horizontal member when said rod member is in rigid engagement with the ground, and a tubular member adapted to be rotatably received by said rod member and said first aperture so as to be in engagement with and rotatably supported at one end by said pad member with the other end of said tubular member extending vertically above said horizontal member, said other end of said tubular member being adapted to rigidly carry a flag pole.

9. A flag pole and supporting device including in combination a horizontal element having a first aperture therein and at least one vertically depending leg element, the free end of said leg element being adapted to be inserted into the ground so as to be in rigid engagement therewith and thereby support said horizontal element in vertically spaced relation above the surface of the ground, a pad member having a second aperture therein, said pad member being adapted to engage the ground and underlie said horizontal element so that said first and second apertures are in vertical alignment, an elongated rod member adapted to be received within said first and second apertures when they are in vertical alignment and be inserted into the ground so as to be in rigid engagement therewith, said rod member being of sufficient longitudinal extent so as to extend vertically above said horizontal member when said rod member is in rigid engagement with the ground, a tubular member adapted to be rotatably received by said rod member and said first aperture so as to be in engagement with and rotatably supported at one end by said pad member with the other end of said tubular member extending vertically above said horizontal member, said other end of said tubular member being adapted to rigidly carry a flag pole and a flag pole including a plurality of tubular sections adapted to telescope within one another when not extended in operative relation.
